(57) CLAIM

The ornamental design for a speaker box, as shown and described.

DESCRIPTION

FIG. 1 is a perspective view of a speaker box of my new design;

FIG. 2 is a front view of the speaker box shown in FIG. 1;
FIG. 3 is a rear view of the speaker box shown in FIG. 1;
FIG. 4 is a left side view of the speaker box shown in FIG. 1;

FIG. 5 is a right side view of the speaker box shown in FIG. 1;
FIG. 6 is a top view of the speaker box shown in FIG. 1; and,
FIG. 7 is a bottom view of the speaker box shown in FIG. 1.

The broken line portions of the disclosure are for illustrative purposes only and form no part of the claimed design.
